UNITED STATES PATENT OFFICE.

HARRY T. SHEARER, OF WAYNESBORO, PENNSYLVANIA.

GRINDING-MACHINE.

1,113,914.

Specification of Letters Patent.

Patented Oct. 13, 1914.

Application filed April 19, 1913. Serial No. 762,360.

To all whom it may concern:

Be it known that I, HARRY T. SHEARER, a citizen of the United States, residing at Waynesboro, Franklin county, and State of Pennsylvania, have invented and discovered 5 certain new and useful Improvements in Grinding-Machines, of which the following is a specification.

My said invention consists in an improved 10 construction and arrangement of parts of automatic cross feed mechanism for the grinding wheels of grinding machines, whereby such a mechanism is provided which is positive in its action and which operates during the period of the tarry of the 15 grinding wheel carriage at each reversing point, all as will be hereinafter more fully described and claimed.

Referring to the accompanying drawings, 20 which are made a part hereof and on which similar reference characters indicate similar parts, Figure 1 is a rear view of a portion of a grinding machine of the "Landis" type illustrating the portions of the mechanism to which my said invention relates; Fig. 2 a detail elevation of the parts as seen when looking in the direction indicated by the arrows from the dotted line 2—2 in Fig. 1; Fig. 3 a detail plan view of the gearing 25 separate from the framework, showing its relative arrangement, one part to another; and, Fig. 4 a detail view on the dotted line 4—4 in Fig. 3.

In said drawings the portions marked A 30 represent the grinding wheel carriage; B the grinding wheel base; and C the transverse slide on top of the carriage on which said base is adapted to move to feed the grinding wheel to and from the work. All of 40 these parts are substantially of the well-known "Landis" type and their construction and arrangement being well understood need not be further explained except incidentally in describing the invention.

45 The mechanism for feeding the grinding wheel to the work comprises a rack 10, secured to the slide C with which a pinion 11 on the lower end of a vertical shaft 12 is adapted to engage. Said shaft 12 is journaled in grinding wheel base B and has a worm gear 13 on its upper end with which a worm 14 on the end of a horizontal shaft 15 engages. Said shaft 15 is supported in appropriate bearings on the carriage and 55 carries a ratchet feed wheel 16 on its outer end adapted to be operated by a pawl 17

connected with a reciprocating member 18 through the medium of angle lever 19 pivoted at 20 and connected with said reciprocating member by pivot 21. Said angle lever 19 has a segment gear 22 on its upper end adapted to engage with a similar gear 23 on the lower end of an angle arm 24 pivoted at 25 and carrying said pawl 17 on its outer end. Said reciprocating member 18 is in the form of a weight and at its lower end rests on arm 70 on one side of a housing 26 carried on the upper end of the plunger 27. Said plunger is mounted in a suitable hollow standard 28 carried by the 70 grinding wheel carriage.

A rack bar 29 is mounted to have a limited sliding movement on the under side of the grinding wheel carriage and a rod 30 is connected therewith by a slot 34 and pin 35. 75 Said bar extends between a fixed roller 31 mounted in the lower end of standard 28 and another roller 32 mounted on a horizontal pivot carried by the lower end of plunger 27. A diamond-shaped cam 33 is 80 formed or mounted on said rod 30 adjacent to said rollers 31 and 32. The slot and pin connection with said sliding rack 29 permits a limited independent movement of said rod for a purpose to be presently described. 85 Another rack bar 36 is fixed on the grinding wheel carriage A with which a pinion 37 on a horizontal transverse shaft 38 is adapted to engage; said shaft 38 is supported in suitable bearings, (not shown) on the machine 90 frame and has a hand-operating wheel 39 on its outer end by which said carriage may be traversed by hand when desired. A bevel gear wheel 40 is loosely mounted on said shaft 38 and a pinion 41 formed on or 95 secured to the hub of said wheel 40 meshes with a pinion 42 on the horizontal shaft 43 and said shaft 43 has a pinion 44 on its outer end which meshes with the teeth of rack 29. A driving shaft 45 geared to the main driving mechanism (not shown) has a bevel gear wheel 46 meshing with bevel gear wheel 40 on shaft 38 and is provided with a driving clutch part 47 adapted to be shifted by suitable shifting mechanism to engage 100 either with a driving gear wheel 48 or a driving gear wheel 49 according to the direction which it is desired to drive the carriage. Said gear wheels 48 and 49 are driven in reverse directions by the driving 110 mechanism well understood as common to the Landis machine. Automatic reversing

mechanism, comprising a wheel 50 carrying adjustable dogs 51 and 52 adapted to contact with either side of a rocking arm 53 which is connected by a rod 54 to a shifting fork 55, is adapted to shift said clutch part to engage with one of said driving wheels or the other and thus reverse the direction of the carriage. This mechanism is also substantially the same as shown and described 10 in other "Landis" patents and is well known in this type of machine.

The operation of the mechanism which constitutes the leading features of my present invention is as follows: The machine being in operation and the parts being in the position illustrated in Fig. 1, the carriage is about to reverse and start to travel in the direction indicated by the large arrow at the top in said figure. The power is transmitted, as above described, from the driving shaft 45 through the gears 46 and 40 to the shaft 43 which, through the rack 29, operates the carriage back and forth. As the carriage reaches the limit of its movement 15 in one direction and the clutch part 47 is thrown, through the mechanism before described, from one driving gear to the other. The first movement of the gear will operate through the connections above mentioned to 20 slide rack 29 in the direction indicated by the small arrow on the under side in Fig. 1, and to draw cam 33 from the outside contact with rollers 31 and 32 between said rollers. As said cam rides up over the lower 25 roller 31, it elevates plunger 27, reciprocating member 18 and the connected parts, and operates shaft 12 and, through its connection with the rack 10, feeds carriage B forward, carrying the grinding wheel one step 30 through the connections above mentioned to 35 roller 31, it elevates plunger 27, reciprocating member 18 and the connected parts, and operates shaft 12 and, through its connection with the rack 10, feeds carriage B forward, carrying the grinding wheel one step 40 into the work. The movement of said rack before its contact with shoulder 56 is just sufficient to bring the apex of the diamond-shaped cam over the center line of rollers 31 and 32, whereupon the weight of reciprocating part 18, and other parts carried by 45 the plunger 27, serves to slide said rod independently and carry the other end of its slot 34 against pin 35. The end of rack-bar 29 being then against shoulder 56, the carriage A will start to move. This operation insures the positive and accurate feed of the grinding wheel to the work and while the carriage is standing at a tarry so that the 50 extreme ends of the work receive the same amount of grinding and are reduced to the same degree as the other parts of the work being operated upon. The operation is the same at the opposite end of the work, the parts being "set" for the feeding operation 55 by the appropriate end of slot 34 being in contact with pin 35, and continues in this manner until the work is reduced to a predetermined size, automatically regulated by mechanism common to this type of machine 60 and not shown or described herein.

Rack 36 operates through shaft 38 to turn wheel 50 carrying dogs 51 and 52 set to operate the reversing mechanism at the desired points. Hand wheel 39 may be used to traverse the carriage A by hand, as for 70 setting, adjustment, etc.

Having thus fully described my said invention, what I claim as new, and desire to secure by Letters Patent is:

1. An automatic cross feed for the grinding wheel of grinding machines comprising a reciprocating rack-bar mounted on the grinding wheel carriage and adapted to move independently thereof for a limited distance, feed mechanism connected with 75 the grinding wheel base, a reciprocating plunger for operating said mechanism, and a cam connected with said rack-bar to have a limited independent movement and mounted to operate said plunger, substantially as set forth.

2. An automatic feed mechanism for the grinding wheel of grinding machines comprising a wheel base, the grinding wheel carriage on which the wheel base is mounted, a rack-bar carried on said grinding wheel carriage and mounted to have a limited independent movement, gearing connected with said rack-bar for operating the carriage, reversing mechanism, gearing for 90 feeding said wheel base forward step by step, a vertically reciprocating plunger connected to operate said feeding mechanism, and a cam mounted to operate said reciprocating plunger and connected with said rack-bar to have a limited independent movement, substantially as set forth.

3. In a grinding machine the combination of a grinding wheel carriage, a grinding wheel base mounted to slide transversely on 95 said carriage, mechanism for feeding said grinding wheel base toward and from the work step by step, a reciprocating plunger mounted on said grinding wheel carriage for operating said mechanism, a cam for 100 operating said plunger, a rack-bar mounted on said grinding wheel carriage to have a limited independent movement, a connection between said rack-bar and said cam adapted to permit a limited independent movement between said parts, and gearing connecting said rack-bar with the driving mechanism, substantially as set forth.

4. In a grinding machine the combination of a grinding wheel carriage, mechanism for traversing said carriage, a grinding wheel base mounted to slide transversely on said carriage, mechanism for sliding said wheel base step by step, a reciprocating plunger for operating said mechanism, and a cam for operating said plunger connected to said grinding wheel carriage, substantially as 115 set forth.

5. In a grinding machine the combination of a grinding wheel carriage, a grinding 120

- wheel base mounted to slide transversely thereon, mechanism for sliding said grinding wheel base step by step, a reciprocating plunger for operating said mechanism, a cam for reciprocating said plunger, a rack-bar on said carriage connected with said cam, and traversing and reversing mechanism geared to said rack-bar, substantially as set forth.
6. In a grinding machine the combination of a grinding wheel carriage, a grinding wheel base mounted to slide transversely on said carriage, means for traversing said carriage back and forth, comprising a rack mechanism for sliding said grinding wheel base across said carriage, and a cam connected to said rack and arranged to be operated by the traverse of the carriage for operating the mechanism for sliding said wheel base, substantially as set forth.
7. A grinding machine comprising a grinding wheel carriage, means for traversing said carriage, a grinding wheel base mounted to slide across said carriage, mechanism for feeding said grinding wheel base step by step, and a cam for operating said mechanism connected to said grinding wheel carriage to have a limited independent movement whereby the feed of the grinding wheel to the work is accomplished during the tarry of the carriage at each reverse thereof, substantially as set forth.
8. A grinding machine comprising a grinding wheel carriage, a grinding wheel base mounted to slide across said carriage, means for operating said base to feed the grinding wheel step by step to the work, a reciprocating part for operating said mechanism, a cam for operating said reciprocating part, a rack-bar mounted on the grinding wheel carriage to slide independently thereof for a limited distance, a connection between said rack-bar and said cam to permit a limited independent movement, driving mechanism, and gearing connecting said driving mechanism with said rack-bar, substantially as set forth.
9. A grinding machine comprising a grinding wheel carriage, a grinding wheel base mounted to slide across said carriage, mechanism for feeding said grinding wheel base step by step to the work, an operative connection between said mechanism and the grinding wheel carriage embodying a rack-bar having a limited independent movement, gearing connecting said rack-bar with the driving mechanism, said driving mechanism embodying a reversing gear, means for operating said reversing gear, a second rack-bar fixed upon said grinding wheel carriage, and a connection between said rack-bar and the means for operating said reversing gear, substantially as set forth.

In witness whereof, I have hereunto set my hand and seal at Waynesboro, Pennsylvania, this 21st day of March, A. D. nineteen hundred and thirteen.
